S. A. A. STENBERG.
PIN AND NEEDLE CUSHION.
APPLICATION FILED JUNE 19, 1919.

1,357,086.

Patented Oct. 26, 1920.

Inventor:
S. A. Allan Stenberg.

UNITED STATES PATENT OFFICE.

SVEN AXEL ALLAN STENBERG, OF LOS ANGELES, CALIFORNIA.

PIN AND NEEDLE CUSHION.

1,357,086.

Specification of Letters Patent. Patented Oct. 26, 1920.

Application filed June 19, 1919. Serial No. 305,399.

To all whom it may concern:

Be it known that I, SVEN AXEL ALLAN STENBERG, a citizen of Sweden, residing at Los Angeles, in the county of Los Angeles and State of California, have invented a new and useful Pin and Needle Cushion, of which the following is a specification.

My invention relates to improvements in cactus-shaped pin and needle cushions, and the objects of my improvement are, first, to provide a novel and ornamental cactus-shaped pin and needle cushion that may be easily and cheaply manufactured and assembled mechanically, and second to provide said cushion with special perforations and apertures in which the pins and needles,—which in a cushion of this character, resemble the spines and needles of a cactus-plant,—may be conveniently and artistically grouped and affixed.

I attain these objects by the arrangement and combination of parts hereinafter described and claimed, and while the invention is not restricted to the exact details of construction disclosed or suggested herein, still for the purpose of illustrating a practical embodiment thereof, reference is had to the accompanying drawings, in which similar numerals refer to similar parts throughout the several views, and in which—

Figure 1 is a vertical side view showing one form of my invention complete; Fig. 2, a perspective view of a cactus shaped form or mold hereinafter described; Fig. 3, a perspective view of a cactus shaped portion of fabric hereinafter described; Fig. 4, a perspective view of a partition hereinafter described; Fig. 5, a perspective view of a mirror image of the form shown in Fig. 2; Fig. 6, a perspective sectional detail view of a part of the cushion on the line 1, 1, Fig. 1; and Fig. 7, a side view of a portion of a pin cushion broken off at its lower end to show more clearly, in the drawing, apertures hereinafter described.

Referring to Fig. 2, I show a flat irregular and cactus shaped standard or form 2, that may be made of any suitable material such as wood, clay, metal, cement or papier mâché but that for the purpose of this description may be regarded to be made of thin metal, said form 2 being provided with a plurality of perforations or apertures 3, and also having an inwardly projecting and continuous rim 4 along its outer edges.

A mirror image of the form 2,—slightly

larger,—but in other respects a similar form or mold 5 is shown in Fig. 5.

In assembling the cushion, a cactus shaped portion 6, Fig. 3, of cloth or other fabric or material, is fitted and glued to the inner surfaces of each of the two opposite forms or molds 2 and 5, whereafter said shells or molds are filled with a suitable resilient composition or other desired material, the cloth or fabric 6 preventing the resilient composition or filling from escaping through the perforations. The cloth or fabric 6, should be of a suitable rough and fuzz like texture on the surface adjacent to the perforations; tuft like portions of said cloth or fabric being pressed through and protruding through said perforations and thereby, in a degree resembling the fuzz or growth of the minute spines that usually grow around the larger spines and needles in a cactus plant of the kind which this device imitates. For the purpose of preventing pins and needles from being accidentally thrust entirely through the cushion from a perforation on one side of the cushion through a perforation on the opposite side of the cushion, a cactus shaped partition 7, Fig. 4, is inserted between the two molds 2 and 5 with their respective filling, whereafter the two forms are placed rim against rim and joined in this position, the rim of the form 5 being slightly larger than the rim of the form 2 and partly or entirely overlapping the rim of the mold 2. The two molds incasing the interior filling may be permanently fastened together in this position by means of solder, glue or other medium dependent on the material used in the manufacture of the molds 2 and 5.

Figs. 2 and 5 show the two opposite molds 2 and 5 as having rims 4 and 4 bent at a sharp angle; whereas Fig. 1 and particularly Fig. 6, show the molds 10 and 11, (inclosing the filling 8, the fabric or inside covering 6, and the partition 7), as having curved rims, and the mold 10, in Fig. 6, as being in addition provided with a small continuous and projecting stop-rib 9, which when employed runs entirely around said form. Either type may be used as preferred.

The outer surfaces of the two forms are colored preferably green to resemble the color of cactus, and in the apertures 3, one, or any desired number of pins and needles 17, are grouped and affixed, and penetrat-

ing into the incased and resilient interior are held firmly in place.

The cushion may be mounted, or form a part of any desired article such as a sewing box, receptacle or novelty, or, as in the drawing, be affixed to a tray-like lid 12, serving as a cover for the round sewing box 14. The lower ends of the forms 2 and 5 are provided with extensions 13, 13, (Figs. 2 and 5), which may be soldered or otherwise securely affixed to the tray 12 after the cushion has been assembled as hereinbefore described.

A solid cactus-shaped core of cement, clay, 15 plaster Paris, or other material may be substituted for the resilient core hereinbefore described, said solid core 15,—a portion of which is shown in Fig. 7,—being made, when employed, to fit snugly within the 20 incasing molds. At each perforation of the inclosing molds, the core 15 is punctured correspondingly, to a desired depth and at a desired angle and the apertures 18 thus formed may be filled with a resilient mate- 25 rial such as cork, cloth, fibrous twine, or other material, glued or otherwise affixed to the interior of the apertures. In Fig. 7 a pencil or tuft of fibrous twine 16, is shown ready to be inserted, while in the same figure three apertures are shown with the inserted pencils in place. In the filled apertures 18, pins and needles 17, representing 30 spines and needles of a cactus, are affixed and retained, while the resilient filling re-

sembles the minute tuft-like spines or fuzz 35 of a cactus plant. The solid cactus shaped core 15 is colored green, preferably, to resemble the color of a cactus plant, and this core may, or may not,—as preferred,—be incased in enveloping molds similar to the 40 molds hereinbefore described. When the solid core 15 is incased in the inclosing molds these latter in time may become scratched and worn in appearance from usage and the inclosing molds may then be removed from 45 the core when the remaining core will serve the purpose of the original pin cushion equally well and, besides, appear new and fresh.

When the solid core 15 is manufactured 50 without the incasing molds, the core may be attached in any desired manner to any useful tray, receptacle or other novel device.

I claim:

The combination in cactus-shaped pin and 55 needle cushions of two opposite, rigid, perforated and cactus-shaped molds or shells, said shells or molds assembled snugly together, the two shells or molds inclosing an interior resilient cactus-shaped filling, pins 60 and needles arranged to resemble the spines and needles of a cactus plant grouped and affixed in the apertures formed by the perforations, the whole affixed to a useful support, all substantially as set forth and for 65 the purpose specified.

S. A. ALLAN STENBERG.
